UNITED STATES PATENT OFFICE.

FABIAN A. ZEMOJTEL, OF PHILADELPHIA, PENNSYLVANIA, ASSIGNOR OF ONE-THIRD
TO JOSEPH SOBOLEWSKI, OF PHILADELPHIA, PENNSYLVANIA.

INK-WELL.

1,246,214.

Specification of Letters Patent.

Patented Nov. 13, 1917.

Application filed July 20, 1917. Serial No. 181,920.

To all whom it may concern:

Be it known that I, FABIAN A. ZEMOJTEL, a citizen of Russia, residing at Philadelphia, in the county of Philadelphia and State of Pennsylvania, have invented certain new and useful Improvements in Ink-Well, of which the following is a specification.

This invention relates to new and useful improvements in ink wells.

10 The primary object of the invention is the provision of an ink well adapted for regulating the amount of ink serviceable for writing purposes and for readily renewing the same from a storage portion of the device.

15 A further object of the invention is the provision of an ink well adapted for storing a quantity of writing fluid, and provided with a serviceable well in which the depth of the fluid is regulated at will so that only 20 a small required amount may be obtained therein readily renewable when found desirable.

With these general objects in view and others that will appear as the nature of the 25 invention is better understood, the same consists in the combination and parts herein-after fully described and illustrated in the drawing and pointed out in the appended claims.

30 In the drawing forming a part of this application and in which like designating characters refer to corresponding parts throughout the several views,

Figure 1 is a view of the device partly in 35 side elevation and partly in central longitudinal section.

Fig. 2 is a central sectional view thereof.

Fig. 3 is a top plan view of the same and

40 Fig. 4 is a central sectional view of a slightly modified form of the device.

Referring more in detail to the drawing the device broadly consists of a body 10, formed of such material as glass with a storage chamber 11 for writing fluid formed 45 therein. The body 10 is preferably in the form of a truncated cone having an axially arranged recess or socket 12 opening at the top 13 of the body 10 and being downwardly 50 tapered forming a seat 14 at the bottom thereof.

A port 15 is arranged between the chamber 11 and the socket 12 while the well or cup 16 is mounted in the socket 12 and 55 forming thereto in shape, with the bottom

17 of the cup seated upon the bottom 14 of the socket 12 while the perforation 18 is arranged through said cup bottom 17. A projecting flange 19 is provided at the top of the cup 16 preferably having a roughened 60 outer end 20 for convenience in grasping when desired to revolve the cup 16 relatively of the body 10. A passage 21 is provided through the wall 22 between the socket 12 and the chamber 11, whereby the 65 chamber 11 may be readily supplied with ink as 23 through the said passage 21 when the cup 16 is removed. It is to be noted that the opening 21 in addition to functioning as a filing opening, may more importantly be utilized as an exit opening, its position relative to the outer end of the container permitting the entire contents of the container being emptied. When the ink in the container 10 is allowed to remain for a 70 sufficient length of time without being used, the same will thicken and cling to the bottom and side walls of the container, which necessitates a flushing with clean water to remove same. It is only necessary to invert 75 the container and permit the entire contents being removed by way of the opening 21.

The operation of the device will be apparent from this description thereof, it being understood that a supply of ink 23 being provided in chamber 11, with the cup 16 in its normal position in socket 12, and with the perforation 18 out of alignment with the port 15 whereby said port is normally closed preventing the flow of ink 23 from the 80 chamber 11 into the cup 16. By grasping the end 20, the cup 16 may be turned for bringing the perforation 18 in alignment with the port 15 and thereby permitting the ink to fill the cup 16 to the desired height, 85 and whereupon the cup is again turned preventing the further entering of ink into the same.

It is often desired to maintain the depth 90 of the ink within an ink well, substantially the same at all times, and this can be readily accomplished by the present device. In the modified form of construction shown in Fig. 4, the body 10' is provided with an ink chamber 11' therein, while a funnel shaped 95 wall 22' centrally depends into the said chamber having a bottom 14' provided with a port 15' throughout for communicating with the ink chamber 11'. A tapered cup 16' is journaled within the socket 12' pro- 100 105 110

vided centrally of the wall 22', the said cup having a perforation 18' adapted to register with the port 15' for supplying ink to the cup 16'.

5 While the forms of the invention herein shown and described are what are believed to be the preferable employments thereof, it will nevertheless be understood that minor changes may be made therein without departing from the spirit and scope of the invention as claimed.

What I claim as new is:—

An inkwell of the type described, including a body-portion having a storage chamber, said storage-chamber having a downwardly tapered socket-member therein hav-

ing a ported bottom, said ported bottom being spaced off from the bottom of the storage-chamber to form a communication therebetween through the port of said bottom, 20 and a cup forming the well proper of corresponding tapered outline as said socket-member and fitting therein and having a port in its lower end adapted initially to occupy a position out of alinement with the 25 port in the bottom of said socket-member, and to be brought into alinement with said latter referred to port in supplying the ink-well with ink.

In testimony whereof I affix my signature. 30

FABIAN A. ZEMOJTEL.
